CLAIM

The ornamental design for a sawhorse, as shown and described.

DESCRIPTION

FIG. 1 is a top, front, right side perspective view of a sawhorse showing our new design;

FIG. 2 is a front elevational view, the rear elevational view being a mirror image thereof; and

FIG. 3 is a right side elevational view, the left side elevational view being a mirror image thereof.

FIG. 1

FIG. 2

FIG. 3
